DESIGN FOR A RANGE OR SIMILAR ARTICLE

Donald L. Hadley, Mansfield, and Clifford A. Sipe, Shelby, Ohio, assignors to Westinghouse Electric & Manufacturing Company, a corporation of Pennsylvania

Application March 28, 1936, Serial No. 61,838

Term of patent 7 years

To all whom it may concern:

Be it known that we, Donald L. Hadley and Clifford A. Sipe, citizens of the United States, residing, respectively, at Mansfield and Shelby, in the county of Richland and State of Ohio, have invented a new, original, and ornamental Design for a Range or Similar Article, of which the following is a specification, reference being had to the accompanying drawing constituting a part

thereof in which the figure is a perspective view of a range showing our new design. The dominant features of our design reside in the portions shown in full lines.

We claim:

The ornamental design for a range or similar article substantially as shown and described.

DONALD L. HADLEY.

CLIFFORD A. SIPE.
